(Cl. D52—2)

To all whom it may concern:

Be it known that I, Robert A. Gageby, a citizen of the United States, residing in Van Nuys, in the county of Los Angeles and State of California, have invented a new, original, and ornamental Design for Cabinet for Test Equipment, of which the following is a specification, reference being had to the accompanying drawing, forming part thereof.

Fig. 1 is a front perspective view of a cabinet for test equipment, showing my new design;

Fig. 2 is a front elevational view; and

Fig. 3 is a rear elevational view thereof.

I claim:

The ornamental design for a cabinet for test equipment, as shown.

ROBERT A. GAGEBY.
